CLAIM

The ornamental design for a soap on a stick, as shown and described.

DESCRIPTION

FIG 1 is a top isometric view of my first embodiment for a soap on a stick;

FIG. 2 is a top plan view thereof, the bottom plan view being a mirror image thereof;

FIG. 3 is a front view thereof, the back side view being a mirror image thereof;

FIG. 4 is a top plan view of my second embodiment for a soap on a stick, the bottom plan view being a mirror image thereof;

FIG. 5 is a front view thereof, the back side view being a mirror image thereof;

FIG. 6 is a right side view of the first embodiment, the left side view being a mirror image thereof;

FIG. 7 is a right side view of the second embodiment, the left side view being a mirror image thereof;

FIG. 8 is a perspective view of the second embodiment; and,

FIG. 9 is a perspective view of the first embodiment.

The first embodiment has a round stick and the second embodiment has a square stick.

The broken lines shown in the drawings illustrate environment for the article and form no part of the claimed design.
